UNITED STATES PATENT OFFICE.

THURMAN MAX CONREY, OF WICHITA FALLS, TEXAS.

DRILL OR CORING TOOL.

Application filed April 23, 1925. Serial No. 25,391.

To all whom it may concern:

Be it known that I, THURMAN M. CONREY, a citizen of the United States, residing at Wichita Falls, in the county of Wichita, 5 State of Texas, have invented certain new and useful Improvements in Drill or Coring Tools, of which the following is a specification.

This invention relates to a drill or coring tool for use in earth boring, and one of the principal objects of the invention resides in the provision of an improved coring drill bit which may be easily operated to form a core to cut the same off and to bring it out 15 of the well, as well as to effectively drill or form the well hole.

A further object of the invention resides in the provision of a device of this character which is of simple and durable construction, which is positive and reliable in 20 operation and easy and comparatively inexpensive to manufacture.

Other objects and advantages reside in certain novel features of the construction, 25 arrangement and combination of parts which will be hereinafter more fully described and particularly pointed out in the appended claims, reference being had to the accompanying drawings forming a part of this 30 specification, and in which:

Figure 1 is a view partly in elevation and partly in vertical section showing the invention as positioned when drilling the well hole,

Figure 2 is a view in transverse vertical section of the embodiment shown in Figure 1 but illustrating the first step in the re-positioning of the parts to bring about the severance of the core and the retention of the 40 core in the tool,

Figure 3 is a view similar to Figure 2 but showing the parts as positioned when the core has been cut off and the removed section held in the tool.

Figure 4 is a view in transverse section on the line 4—4 of Figure 3, and

Figure 5 is a similar view on the line 5—5 of Fig. 3.

Referring to the drawings, the numeral 1 50 designates the lower end of the drill stem. A tubular driving member 2 has its upper end fastened to the lower end of the drill stem as by means of threads 3.

A tubular cutter head or member 4 is 55 provided and its forward end is enlarged, as at 5, and provided with transverse slots 6.

The lower ends of the slots 6 extend out through the bottom of the cutter head and are contracted to present shoulders 7. Cutters 8 are provided and have enlarged portions 9 fitted in the slots 6. The cutters 8 have a transverse extent greater than the thickness of the lower end of the tubular cutter head 4 and the portions of the cutters 8 which project beyond the outside of the cutter head are engaged by a holding ring 10 which has threaded engagement with the cutter head and which may be turned to forcibly press down on the cutters and bind them against the shoulders 7 whereby to lock 70 and hold them in position.

The adjacent end of the driving member 2 and the cutter head 4 are formed with interengaging means by which the cutter head may be driven from the driving member. This interengaging means preferably 75 comprises alternate projections 11 and recesses 12 on the driving member 2 and corresponding projections 13 and recesses 14 on the cutter head, the projections 11 being received in the recesses 14 and the projections 13 in the recesses 12 when the cutter head is driven from the driving member.

With this arrangement when the parts are positioned as shown in Figure 1 and the 80 drill stem is rotated, the driving member 2 being fastened to the drill stem will also be rotated therewith and the rotary movement of the driving member will be transmitted to the cutter head through the recesses and projections 11, 12, 13 and 14. When the cutter head is thus turned and advanced the cutters 8 will be effective to form a hole or bore in the earth and they will also form 85 a core which will pass up through the opening of the tubular cutter head.

In order to provide for the severance and retention of this core while the drill stem and tool are being raised, core severing and retaining means is provided and comprises 90 a tubular carrier 15 fitted in the driving member 2 and in the cutter head 4. At the lower end of the carrier 15 a plurality of core severing and retaining fingers 16 are 100 provided. The upper ends of the fingers 16 are secured, as at 17, to the lower end of the sleeve 15 but the major portions of the fingers project below the sleeve. The fingers 16 possess some degree of resiliency but are 105 sufficiently heavy and rigid to hold the core when in the position shown in Figure 3. The lower ends of the fingers 16 are curved 110

inwardly, as at 18, and the curved portions 18 are co-operable with a camming shoulder 19 formed on the outer head 4. When the parts are positioned, as shown in Figures 1 and 2, the fingers 17 do not obstruct the passage 20 of the cutter head which leads out through the lower end of the cutter; whereas, as shown in Figs. 3 and 5 the fingers 16 may be moved to form an effective closure or obstruction for this passage so as to prevent the core from falling out of the tool.

It is proposed to control the action of the fingers 16 from the drill stem and to positively operate these fingers from the drill stem. For these purposes the carrier sleeve 15 on which the fingers 16 are mounted is provided at its upper end with lugs 21, four lugs being provided at angular intervals of 90°. The lugs 21 may be positioned in slots 22 formed in the driving member 2 or they may be positioned in an annular clearance space 23 which is formed by machining out the driving member adjacent one end. The slots 22 extend from the clearing space 23 down through the driving member to a point adjacent to but spaced from the lower end of the driving member. The lower end walls of the slots 22 present shoulders 24 which may co-act with the lugs 21 to prevent the tool from falling apart. The lower end of the sleeve 15 is externally threaded, as indicated at 25, and these threads 25 are engaged with threads 26 provided on the inside of the cutter head 24.

When it is desired to remove a section of the core which has been formed by the drilling operation above described, and which has passed up through the interior of the tool through the opening 20, the drill stem is raised and this causes the projections 11 and recesses 12 to be moved away from the projections 13 and recesses 14 and also causes the slots 22 to be elevated until the lugs 21 are positioned therein. Now when the drill stem is turned the driving member 2 will, of course, be turned but the cutter head 4 will tend to remain stationary due to the engagement of the cutter teeth 8 with the earth and to the inertia of the cutter head and its parts. The sleeve 15 will, however, be turned with the driving member 2 since the lugs 21 and slots 22 provide a driving connection at this time. When the sleeve 15 is so turned it will be advanced down through the cutter head due to the action of the threads 25 and 26 and the movement of the sleeve 15 down through the cutter head will cause the fingers 15 to slide down the cam shoulder 19 and to be urged inwardly from the position shown in Figures 1 and 2 to the position shown in Figure 3. This movement of the fingers will result in a severance of the core, the outer ends of the fingers being sharpened sufficiently to enable them to perform this

severing action. The fingers not only serve to sever a section core but also to hold the sections so severed within the tool.

I claim:

1. In a tool of the character described, a tubular cutter head, a driving member, means whereby the cutter head may be actuated from the driving member or disconnected therefrom, normally inactive core-holding means for positively moving said core-holding means to core-holding position when the driving member is disconnected from the cutter head and rotated.

2. In a tool of the character described, a cutter head having cutters at its forward end, a driving member, interengageable means between the driving member and the cutter head, a carrier fitted within the driving member and within the cutter head, normally inactive core-holding devices mounted on said carrier, said cutter head having means to project the core-holding devices when the carrier is advanced therethrough, and positive means operable from the driving member for advancing the carrier through the cutter head.

3. In a tool of the character described, a cutter head having cutters at its forward end, a driving member, interengageable means between the driving member and the cutter head, a carrier fitted within the driving member and within the cutter head, core-holding devices mounted on said carrier, said cutter head having means to project the core-holding devices when the carrier is advanced therethrough; and means operable from the driving member for advancing the carrier through the cutter head and including a screw threaded connection between the carrier and the cutter head, and a driving connection between the carrier and the driving member.

4. In a tool of the character described, a tubular cutting head having cutters at its forward end, a tubular drive member, interengageable recesses and projections on the driving member and on the cutter head, a carrier sleeve fitted within the cutter head and the driving member, said carrier sleeve having outwardly projecting lugs at its upper end and having external screw threads at its lower end, said driving member having a clearance space designed to accommodate the lugs and also having lengthwise slots in which the lugs may be received to provide a driving connection between the driving member and the sleeve, said cutter head having internal screw threads engaged with the external screw threads of the carrier sleeve, a plurality of resilient fingers mounted on the carrier sleeve and tensioned to normally lie substantially flat up against the inner wall of the cutter head, the cutter head having a camming shoulder cooperable with the fingers

when the sleeve is advanced to cause the fingers to be projected across the mouth of the cutter head.

5. In a tool of the character described, 5 a tubular cutting head having cutters at its forward end, a tubular drive member, interengageable recesses and projections on the driving member and on the cutter head, 10 a carrier sleeve fitted within the cutter head and the driving member, said carrier sleeve having outwardly projecting lugs at its upper end and having external screw threads at its lower end, said driving member having a clearance space designed to

accommodate the lugs and also having 15 lengthwise slots in which the lugs may be received to provide a driving connection between the driving member and the sleeve, said cutter head having internal screw threads engaged with the external screw 20 threads of the carrier sleeve, a plurality of core-holding and severing devices mounted on the carrier and adapted to be normally inactive, and means on the cutter head for projecting said devices when the carrier 25 sleeve is advanced through the cutter head.

THURMAN MAX CONREY.
